(57) **CLAIM**

The ornamental design for a rear bumper for an automobile or replica, as shown and described.

DESCRIPTION

FIG. 1 is a front and left side perspective view of a rear bumper for an automobile or replica showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The ghosted or low contrasted structures in the drawings illustrate portions of the rear bumper for an automobile that form no part of the claimed design. The drawings include grayscale surface shading which illustrates contour, not any particular color.
